INVENTOR
BY Victor J. Evans & Co.
ATTORNEY

WITNESS:

UNITED STATES PATENT OFFICE

2,049,373

RECEPTACLE

Homer A. Hampe, Spindale, N. C.

Application September 5, 1934, Serial No. 742,834

2 Claims. (Cl. 220—55)

This invention relates to receptacles, and its general object is to provide a closure or lid for a receptacle with a securing device that includes latching means for normally holding the lid in closed position and with locking means to hold the latching means against movement, so that casual actuation thereof is impossible, with the result the device is extremely useful for application to a refuse can lid to prevent animals from gaining access to the can, but of course is applicable to any type of receptacle.

A further object of the invention is to provide a securing device for the closure of a receptacle, than can be manually actuated in an easy and expeditious manner and the latching means includes handle means for the closure, so that the latter can be removed substantially simultaneously with the unlatching action.

A further object of the invention is to provide a securing device for the closure of a receptacle, that is simple in construction, inexpensive to manufacture, and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a perspective view illustrating the application of my securing device to a receptacle and its lid.

Figure 2 is a sectional view taken approximately on line 2—2 of Figure 1, looking in the direction of the arrows.

Figure 3 is a top plan view of Figure 1.

Figure 4 is a fragmentary enlarged sectional view showing the latching means in fixed or locked position.

Referring to the drawing in detail, it will be noted that I have illustrated my securing device as being applied to a can and its lid that is generally used for refuse, but I want it understood that the device can be applied to any type of receptacle and lid capable of use therewith, without departing from the spirit of the invention.

The receptacle or can as shown includes the usual body 1 of cylindrical formation and which is provided at intervals about the circumference thereof and adjacent to its upper end with elong-

ated recesses 2 for a purpose which will be presently described.

The lid as shown is indicated by the reference numeral 3 and includes the usual depending flange 4 for disposal about the upper end of the body 5 of the can as best shown in Figure 2.

The securing device includes two or more levers, there being three shown for the purpose of illustration and these levers which are indicated by the reference numeral 5 are pivotally secured 10 to the lid 3 intermediate their ends, through the instrumentality of substantially U-shaped brackets 6 that are riveted or otherwise secured to the lid as shown, with the levers pivotally mounted on pins 7 that bridge the apertured ears of the 15 brackets.

The levers follow the shape of the lid for the major portion of their length and extend into depending portions 8 that terminate in inwardly directed ends or hooks 9 to be disposed in the recesses 2, as best shown in Figure 2, and are held accordingly by coil springs 10, there being a coil spring for each lever, and the coil springs have their lower convolutions received in sockets 11 arranged in the lid, while the upper convolutions are received by bosses 12 that are formed with and depend from the levers as best shown in Figure 4.

The levers radiate from adjacent the center of the lid and terminate at their inner ends into upwardly directed arms 13 which are normally vertically disposed and act in the capacity as handles for moving the levers on their pivots against the coil springs 10 for disposing the hooks 9 out of the recesses 2 so that the lid can 35 be removed from the receptacle, as will be apparent. This action is accomplished by grasping the arms 13 and pressing them toward each other, with the result it will be noted that the latching means can be actuated to an unlatched 40 position substantially simultaneously with the removal of the lid from the receptacle or can, as the arms 13 act in the capacity as handles for the lid.

While the lid is normally held in closed position 45 through the instrumentality of the latching means above described, I also employ locking means for the latching means and this locking means in the form as shown includes cam means 14 of substantially cup-shape configuration in that 50 it is provided with a disk-shape base 15 that is rotatably mounted centrally of the lid by a headed pin 16 which extends through the base and lid as best shown in Figure 4.

The cam means as shown is provided with 55

three cam members 17 that are arranged in ratchet formation and are formed with the base, with their upwardly inclined surfaces arranged in the path of lugs 18 that depend from the 5 levers at the juncture of the arms 13 therewith as best shown in Figure 4. The cam members each terminate in a vertical shoulder at the highest point of their inclination and the lowest point of the cam members extend from the 10 shoulders, as best shown in Figure 1.

In view of the fact that there is a cam member for each lever, the latter are held in fixed or locked position when the lugs 18 contact the highest point of the inclined surfaces, but when 15 it is desired to release the levers the cam member is rotated on its pin 16 for disposing the lugs beyond the shoulders so that the latching means can be actuated to unlatched position, there being ample space for that purpose, at the 20 lowest point of the cammed or inclined surfaces, therefore it will be seen that the latching means can be locked or held against casual movement, or released, merely by rotating the cam means.

It is thought from the foregoing description 25 that the advantages and novel features of my invention will be readily apparent.

I desire it to be understood that I may make changes in the construction and in the combination and arrangement of the several parts, provided that such changes fall within the scope 30 of the appended claims.

What I claim is:

1. A securing device for the closure of a receptacle, comprising latching means including 35 levers pivotally secured to the closure, said receptacle including keeper means, hook means

formed on the levers and received in the keeper means when the latching means is in operative position to hold the closure on the receptacle, handles formed on the levers, and locking means to hold the latching means in operative position, 5 said means comprising a cup shaped member which is centrally pivoted for finger rotation on the outer face of the closure and which has its peripheral and outstanding flange stepped to define straight vertical shoulders and inclined walls 10 between said shoulders and upon which walls the levers normally rest.

2. A means for removably securing a flanged closure on the mouth of a receptacle, comprising a series of radially disposed levers spaced from 15 but pivoted to the outer face of the cover and having outer hook ends to engage with the receptacle and having inner offset handle ends which are closely related, and expansion springs seated in the cover and engaging the levers to 20 swing the same away from the cover to bring their hooked ends to engage with the receptacle, each of said levers having its inner edge opposite its handle end formed with a depending lug, a finger operated lock for the levers pivoted for 25 rotation on the cover and comprising a cup-like member which has its outstanding peripheral flange formed with outer equi-distantly spaced inclined walls and with straight connecting walls 30 or shoulders between the highest and lowest points of said inclined walls, and the springs for the levers normally influencing the lugs on said levers against the inclined walls of the finger operated lock.

HOMER A. HAMPE. 35
